METHOD AND APPARATUS FOR WRAPPING
CYLINDRICAL ARTICLESAlbertus Hendrik Haupt, Somerset West, Union
of South Africa, assignor to Imperial Chemical
Industries Limited, a corporation of Great
BritainApplication March 31, 1934, Serial No. 718,490
In Great Britain April 1, 1933

5 Claims. (Cl. 93—2)

This invention relates to an improved method and apparatus for wrapping cylindrical articles, especially cylinders of gelatinous or plastic blasting explosives or other plastic or semi-plastic materials which require delicate handling. At 5 present cylinders of gelatinous blasting explosives are wrapped by hand, or the gelatinous material is extruded into previously formed cylindrical shells. It has also been proposed to wrap cylinders of plastic explosives in paper by means of a machine in which a stationary flat sheet of 10 paper is picked up by a cylinder of the plastic explosive rolling over the sheet. For the action of the machine it is necessary that adhesion should take place between the cylinder and the end of the paper which it first meets in its travel, and if the cylinder itself is not composed of sufficiently sticky material it must be provided with an adhesive.

The principal object of the present invention is to provide a method and apparatus for wrapping cylindrical articles, which when applied to the wrapping of gelatinous or plastic blasting explosives will avoid the disadvantages of the methods referred to in the preceding paragraph, namely, the slowness of hand wrapping, the drawbacks of the process of extrusion into previously formed cylindrical shells (previous preparation of the shells, limited scope of the method), and the use of an adhesive. It should be pointed out that the usual gelatinous or plastic blasting explosives are not sufficiently sticky to cause the adhesion of the waxed or other paper which is generally used for wrapping them.

According to the preferred form of the present invention cylindrical articles are wrapped by feeding them, together with wrapping sheets of the correct size and appropriate shape at appropriate intervals in succession in the same direction 40 along a substantially horizontal endless travelling band which changes direction and takes a downward course at a suitable point, so that the end of the wrapping sheet projects from the horizontal portion of the band.

The cylindrical articles are fed so that at this point a single article is arrested by one of a number of driven rollers which is placed in a position close to the travelling band. Immediately afterwards another driven roller closes behind the cylindrical article, which is confined and given a rotary motion by means of the driven rollers. The wrapping sheet is now conveyed by the belt and passes beneath the roller which has closed behind the cylindrical article, and 55 beneath the cylindrical article, and its leading

edge is turned upwards by one of the driven rollers, and it is wrapped around the cylindrical article. The portions of the wrapping sheet which project beyond the ends of the wrapped article are then folded inwardly and closed by crimping and tapping devices. 5

Two of the driven rollers now move so as to free the wrapped article and it is discharged by the movement of the belt, down the inclined portion of the latter.

My apparatus is best described in relation to the accompanying drawings.

Figures 1, 2, and 3 are diagrams showing respectively the sequence of movements of the rollers which perform the wrapping operation. 15 In the drawings there are shown three wrapping rollers and in practice this number is to be preferred, although more may be employed.

Figure 4 is a side elevation illustrating the general arrangement of a machine incorporating the invention.

Figures 5, 6, and 7 are details of the end closing devices.

Figure 8 is a diagrammatic front elevation looking towards the direction from which the article is being conveyed.

Referring to the drawings, an endless belt 1, of the same width as the length of the cylindrical article to be wrapped, operated at a suitable constant speed, passes over a roller 2, which is free 30 to rotate on the shaft 23, and thence in a downward direction.

Driven roller 3 is carried on arms 6 and 16, whilst rollers 4 and 5 are carried on arms 7 and 20, the drive to these rollers being transmitted 35 by flexible shafts 24 and 29 as well as one not shown driving roller 3. These arms are shown as oscillating about a common shaft 8, but this feature is not essential and they could be arranged to oscillate on separate shafts. The oscillation of the arms 6, 16, 7 and 20 about shaft 8 40 is accomplished by means of cams 9, 32, 10 and 56, mounted on a shaft 11, but other methods of actuating the arms may be employed. It will be understood that only the arms 6 and 7 are shown 45 in Figures 1, 2, 3, and 4.

Cylinders 12 of the gelatinous or plastic material previously cut to the required length, are delivered by suitable means at regular intervals on to the endless conveying belt 1, which moves 50 substantially horizontally until it passes over the roller 2, the cylinders being fed so that their cylindrical axes are and remain substantially parallel to the axes of the rollers. At suitable intervals sheets 13 of wrapping material, broad 55

enough to wrap the cylinders 12 and form the end flaps, are delivered by suitable means on to the belt in correct alignment with the direction of motion of the belt.

5 The movable arms 6 and 16 carrying the driven roller 3 are actuated so that at suitable intervals the roller rises to the position shown in Figure 1 to permit the cylinder 12 to pass underneath; it then descends into the required position for carrying out the wrapping operation as shown in Figure 2. The roller 3 when in this position will permit the wrapping material to pass under it.

10 The conveyor belt 1 carries the cylinder 12 forward a short distance past the roller 3, and changes its own direction downward as it passes over the roller 2, while cylinder 12 is stopped by contact with the driven rollers 4 and 5 on the movable arms 7 and 20 which are suitably inclined so as to bring the rollers 4 and 5 into contact with the article 12. The partial rotation of the arms carrying respectively the roller 3 and the two rollers 4 and 5 is effected by the cams 9 and 32, 10 and 56. Part of the circumference of the roller 5 extends below the plane of the horizontal portion of the conveyor belt and at this stage the roller 5 is in close proximity to the belt as the latter is changing its direction of motion, so that the cylinder 12 remains on top of the horizontal portion of the conveyor belt, and commences to rotate.

15 Meanwhile arms 6 and 16 bearing the roller 3 under which the cylinder 12 has passed have fallen so that the roller 3 is in contact with the cylinder 12.

20 35 The sheet of paper or other wrapping material 13 passes freely under the roller 3 and beneath the cylinder 12. It is then raised and turned backwards by the roller 5 and is wrapped round the rotating cylinder 12 by the combined action 40 of the rollers 5, 4, 3 and the belt 1. After the cylinder 12 has been wrapped, crimping and tapping devices 14 and 57, 15 and 58 come into operation, thus effecting complete closing of the ends 45 of the wrapper. The arms 7 and 20 carrying the rollers 4 and 5 are then moved to the position shown in Figure 3, permitting the wrapped cylinder to be discharged by the motion of the belt 1 and the force of gravity.

50 Thereafter the motion of the shaft 11 through cams 9 and 32, 10 and 56 causes the arms 6 and 16, 7 and 20 to move and the rollers 3, 4 and 5 to take up again the positions shown in Figure 1 to permit repetition of the process.

55 It is to be understood that the movement of the respective arms so as to raise the respective rollers is effected by means of the respective cams but that the movement of the arms in the reverse direction so as to lower the respective rollers is effected by gravity, which may be assisted by 60 springs, the respective cams being moved so as to release the respective arms.

65 Figure 4 of the accompanying drawings illustrates the general arrangement of a machine incorporating the present invention. In this drawing there are represented devices for cutting sheets of wrapping material of suitable size and shape and for cutting cylinders of the plastic material of the required length.

70 The main framework 25 of the machine carries a driving shaft 26. The endless conveyor belt 1 passes over driving rollers on this shaft and on shaft 28 and is supported on free rollers on shafts 23 and 27. The driving shaft 26 drives the shaft 28 by means of sprocket wheels 52 and 53 connected by the chain 54.

75 A sprocket wheel 38 is carried on the shaft 28 and by means of a chain 55 and wheel 39 on shaft 21 drives one of the material cutting rollers 40. The other cutting roller 41 is driven from 40 by means of interrupted gearing. These rollers 5 carry helical knives (not shown) which are adapted to slice the wrapping material into rhomboids.

The wrapping material 13 which is preferably paper is drawn from a roll 22 and guided with the aid of the tensioning guide 42 through the 10 guide rollers 43 and 44 by the cutting rollers 40 and 41, which cut the material to the required shape and deliver it at the required intervals to the conveyor belt 1. In this manner a number of sheets of wrapping material cut to a suitable size 15 and shape are fed in succession on to the belt 1. Sheets cut to the shape of a rhomboid are preferred.

The plastic material to be wrapped is extruded from any suitable type of extruding machine. 20 One such machine is shown in Figure 4, where the material is extruded through an opening 17 under pressure applied by a rotating screw (not shown).

The extruded material is cut into desired 25 lengths by cutters at the ends of a pair of rotating arms 18 which are spaced apart at a distance equal to the desired length of the extended cylinders. As well as cutting the cylinders of plastic material to the required length the cutters also 30 serve to propel the cut cylinders from the platform 19 on to the belt 1.

35 On shaft 21 there is a chain sprocket 45 which is free to revolve on shaft 21 and is driven in the opposite direction to shaft 21 by gear wheels 35 on shaft 28 and on chain sprocket 45. These gears are not shown.

40 Shaft 30 upon which the cutter arms 18 are secured, is driven through chain wheel 45, chain 46 and sprocket wheel 47.

45 In a similar manner the cam shaft 11 is driven from shaft 30 by means of a chain 48 and wheels 49 and 50.

50 By these chains and wheels the correct synchronization of the feeding on to the belt of the 45 wrapping material and the cylindrical article and the raising and lowering of the wrapping rollers are effected. I drive the shafts 21, 30 and 11 at one revolution for each article wrapped. If the shaft 30 carries two or more sets of cutters and 55 multiple cams are fixed to shaft 11, these shafts could be driven at a reduced speed.

55 On the shaft 11 there is a sprocket wheel 72, which, by means of a chain not shown and a sprocket wheel 73, drives a shaft 69 shown in Figure 8 which carries a gear wheel 59 which meshes with a gear 60 on a hollow shaft 61. On this shaft there is another gear 62 not shown. This gear 62 drives a gear 63 which is fixed to the shaft 64 and through the flexible shaft 24 drives 60 the roller 4. Gear 62 also drives the roller 5 through gear 65 and shafts 66 and 29. In a similar manner this gear 62 also drives roller 3 by a gear and shafts not shown. These rollers revolve at such a speed that the peripheral velocity of each is about the velocity of the belt 1. We have found it preferable to make the peripheral velocity of the rollers somewhat higher than that of the belt.

70 Figures 5 and 6 represent different views of 70 the crimping fingers which rotate at interrupted intervals in the same direction of rotation as that of the roller 2 which revolves on shaft 23 upon which they are fixed. The intermittent motion is given to shaft 23 upon which the crimpers 57

and 14 are fixed by a gear wheel 67 and an interrupted gear wheel 68 fixed on shaft 69, the proportions of these gears being such that the shaft 23 makes one revolution and then comes to rest. 5 The fingers 31 are chamfered off on their leading edges as shown at 33 in Figure 5. When the ends of the wrapped article have been crimped in, the fingers come to rest leaving the crimped ends exposed. The tapping rods shown as 15 and 58 10 and in detail in Figure 7 are then advanced towards the crimped ends. The cupped portion 34 first presses the crimped end of the material covering the cylindrical article and as the tapping rod 35 continues to advance the end of this rod 15 presses the centre of the crimped material whilst its periphery is held by the cupped portion 34. The spring 37 causes the portion 34 to resume the position shown in Figure 7 upon the tapping rod 35 being withdrawn from the 20 wrapped article. The advance of the tapping rods 15 and 58 is given by the bakers cams 70 and 71 fixed on the shaft 69 striking the heads of the tapping rods. A spring not shown withdraws the tapping rod when the cam has passed the 25 head 51.

In the above manner the operation of the crimping and tapping devices is synchronized with the completion of the wrapping process.

My invention is particularly suitable for the 30 wrapping of cartridges of gelatinous or plastic materials and has the advantage of a rapid output, while the floor space occupied by the machine is very small in proportion to the output. A machine constructed according to my invention 35 requires only a single operator.

I claim:—

1. The method of wrapping plastic explosive material which comprises arranging the material in a longitudinally extended series of individual 40 cylinders with the cylinders spaced the one from the other, and with individual wrapping sheets interspersed among the cylinders, feeding the thus-arranged assembly forward and arresting the forward travel of each cylinder in turn, confining the cylinder and imparting rotation thereto, feeding the wrapping sheet that is immediately behind such cylinder into contact with the under side thereof, turning the edge of such sheet upward about such cylinder and into confinement therewith, and continuing the rotation of such cylinder while so confined until it is wrapped. 45

2. The method of wrapping plastic explosive material which comprises arranging the material upon a travelling conveyor, in a longitudinally extended series of individual cylinders with the cylinders spaced the one from the other, and with individual wrapping sheets interspersed among the cylinders, feeding the thus-arranged 50 assembly forward to an arresting roller and arresting the forward travel of each cylinder in turn, removing the cylinder from the conveyor and confining the cylinder between rotating rollers, to impart rotation thereto, feeding the wrapping sheet that is immediately behind such cylinder into contact with the under side thereof and into confinement therewith, turning the edge of such sheet upward about such cylinder, and continuing the rotation of such cylinder 55 while so confined until it is wrapped.

3. In a machine for wrapping plastic explosive

material, in combination: a substantially horizontally arranged travelling flexible conveyor, a device delivering individual cylinders of the material in succession to said conveyor to lie thereon, a device delivering individual wrapping sheets in succession to said conveyor to lie thereon, means synchronizing said devices to place a wrapping sheet behind each cylinder, a device spaced along said conveyor from said delivering devices in the direction of travel of said conveyor 10 for turning said conveyor downward creating an angle therein, means arranged above said conveyor and adjacent said angle for arresting the forward travel of each cylinder in turn, directing the forward edge of the following wrapping sheet 15 into contact with such cylinder, and wrapping such sheet about such cylinder, and means for synchronizing such last-named means with said delivering devices. 5

4. In a machine for wrapping plastic explosive material, in combination: a substantially horizontally arranged travelling flexible conveyor, a device delivering individual cylinders of the material in succession to said conveyor to lie thereon, a device delivering individual wrapping sheets 20 in succession to said conveyor to lie thereon, means synchronizing said devices to place a wrapping sheet behind each cylinder, a support spaced along said conveyor from said delivering devices in the direction of travel of said conveyor 25 and about which said conveyor is at least partially wrapped to turn said conveyor downward creating an angle therein, a roller arranged above said conveyor and beyond the conveyor support and movable into the path of said cylinders for arresting the forward travel of each cylinder in turn and directing the forward edge of the following wrapping sheet into contact with such cylinder, a roller movable to position into contact with such cylinder, means for driving at 30 least one of said rollers to wrap such sheet about such cylinder, and means for moving said rollers into coaction with said cylinders in turn in synchronization with said delivering devices. 35

5. In a machine for wrapping plastic explosive material, in combination: a substantially horizontally arranged travelling flexible conveyor, a device delivering individual cylinders of the material in succession to said conveyor to lie thereon, a device delivering individual wrapping sheets 40 in succession to said conveyor to lie thereon, means synchronizing said devices to place a wrapping sheet behind each cylinder, a support spaced along said conveyor from said delivering devices in the direction of travel of said conveyor 45 and about which said conveyor is at least partially wrapped to turn said conveyor downward creating an angle therein, a roller arranged above said conveyor and beyond the conveyor support and movable into the path of said cylinders for arresting the forward travel of each cylinder in turn and directing the forward edge of the following wrapping sheet into contact with such cylinder, a roller movable to a position above and in contact with such cylinder, and a roller 50 movable to a position behind and in contact with such cylinder, means for driving at least one of said rollers to wrap such sheet about such cylinder, and means for moving said rollers in synchronization with said delivering devices. 55
